UNITED STATES PATENT OFFICE.

WILLIAM H. JAMES, OF CINCINNATI, OHIO, ASSIGNOR TO ERNEST H. HUENE-FELD, OF SAME PLACE.

WOOD-BURNING STOVE.

SPECIFICATION forming part of Letters Patent No. 629,191, dated July 18, 1899.

Application filed July 16, 1898. Serial No. 686,126. (No model.)

To all whom it may concern:

Be it known that I, WILLIAM H. JAMES, of Cincinnati, in the county of Hamilton and State of Ohio, have invented certain new and useful Improvements in Wood - Burning Stoves; and I do hereby declare the following to be a full, clear, and exact description of the invention, such as will enable others skilled in the art to which it appertains to make and use the same.

My invention relates to an improvement in wood-burning stoves, and more particularly to the stove shown in Patent No. 600,248, granted me March 8, 1898; and it consists in the parts and combinations of parts, as will be more fully described, and pointed out in the claims.

In the accompanying drawings, Figure 1 is a view in transverse vertical section of my improved stove. Fig. 2 is a view in longitudinal vertical section. Fig. 3 is a horizontal sectional view. Fig. 4 is a detached view of a portion of the inner casing or fire-pot, and Fig. 5 is a view of a modification.

In the stove shown in my Patent No. 600,248 the outer casing is angular and the inner casing or fire-pot curvilinear in horizontal cross-section, the sides of the inner chamber or fire-pot being parallel with the sides of the outer casing, thus forming enlarged air-spaces at the angles of the outer casing and greatly restricted spaces at points intermediate the angles.

In my present invention I have employed a fire-pot curvilinear in vertical cross-section and located horizontally within the angular jacket with its ends adjacent to the front and rear of the jacket and with its curved sides presented toward the bottom sides and top of said jacket.

A represents the outer jacket, open at its lower end and preferably rectangular longitudinally and square transversely. This jacket is mounted on legs *a*, which latter are secured to the lower end of the jacket, at the angles thereof, and hence elevate the lower open end of the jacket above the floor.

B represents the sheet-metal fire-pot, located within and wholly supported by the jacket. This fire-pot has flat ends *b* and *c*, which latter rest in close proximity to the front and

rear faces of the stove, while the bottom, top, and sides of the fire-box are curved. This fire-pot can be of oval or cylindrical shape in transverse vertical cross-section with the centers *d* of its curved sides in close proximity to the sides of the jacket, thus forming restricted passage-ways through which the hot air must pass. With this construction it will be seen that the side passages for the air are enlarged at the extreme bottom of the fire-pot, thus accommodating a large volume of air, and as the base or bottom of the fire-pot is curved it presents a much greater heating and radiating surface than the flat-bottom fire-pot of my patented device. The air as it enters or passes under the jacket is heated, and as it becomes heated it rises. As it rises through the gradually-converging air-passages at the sides the heat becomes more intense and the upward movement more rapid until the air passes the most restricted portions of the passage. By this construction ample space for the reception of the heated air is provided above and at the sides of the fire-pot and for the cold air at the base of the fire-pot.

The top of the jacket is provided with perforations *e* for the free escape of the hot air, and it may also, if desired, be provided at its top with an opening *f*, surrounded by a collar *g*. This collar may form a seat for a perforated hood *E*, or it may be used for the attachment of a hot-air pipe leading to a drum or register in a distant portion of the house, as shown in dotted lines, or it may be a fuel-opening, as shown in Fig. 5.

As shown in Fig. 5, a collar *h* connects the top of the jacket and the fire-pot, the latter being open for the free introduction of the fuel. I prefer, however, to locate the fuel-door at the front, as shown in Figs. 1 and 2, and when so located the front flat end of the fire-pot is slotted, as shown in Fig. 4, to form the four flaps *F*. These flaps are then turned outwardly at right angles to the front face of the fire-pot and again bent inwardly, as at *h*, toward each other and parallel to the front face of the fire-pot. The lips *h* rest against the rear face of the jacket adjacent to the fuel-opening therein, and the door-frame, jacket, and lips *h* are secured together by

bolts. The openings at the four corners, caused by bending the flaps outwardly, are closed by the angle-plates H, which latter are secured to the flaps by bolts or rivets.

5 By employing an angular jacket and a curvilinear fire-pot so located with relation to each other that the side passages for the air are restricted at their centers and enlarged at both extremities the large volume of air 10 at the lower ends of the passages moves upwardly slowly at the start, and hence is subjected for a longer period to the heat, and increases its speed as it passes upwardly. After 15 passing the restricted centers, where the heat is the greatest, the passages again expand and permit of the free and rapid expansion of the highly-heated air.

Air of course passes up between the ends of the fire-pot and adjacent faces of the jacket; 20 but the greater volume passes up between the curved sides of the fire-pot and the sides of the jacket.

It is evident that many slight changes 25 might be resorted to in the relative arrangement of parts herein shown and described without departing from the spirit and scope of my invention. Hence I would have it understood that I do not restrict myself to the exact construction of parts shown and described; but,

Having fully described my invention, what I claim as new, and desire to secure by Letters Patent, is—

1. In a wood-burning heating-stove, the combination of an outer jacket angular in cross-section, of a fire-pot curvilinear in vertical cross-section and having vertical ends, the latter being approximately parallel with the front and rear ends of the angular jacket, the greatest diameter of the curved fire-pot 40 from side to side, being slightly less than the jacket thus forming side air-passages each restricted at a point between its ends, fuel-openings in the front of the jacket and fire-pot and a collar or flange connecting the jacket 45 and fire-pot around said fuel-opening, substantially as set forth.

2. In a wood-burning heating-stove, the combination of an outer jacket angular in cross-section, open at its bottom and provided 50 with air-escape opening in its top, a fire-pot having vertical ends, and located within said jacket, the front end plate of the fire-pot being slitted to form four flaps which are bent, first at right angles to the end plate forming 55 flaps and then toward each other forming lips, angle-plates connecting the flanges at the angles or corners and devices for securing the lips to the jacket.

In testimony whereof I have signed this 60 specification in the presence of two subscribing witnesses.

WILLIAM H. JAMES.
